UNITED STATES PATENT OFFICE.

CHARLES K. WOODBRIDGE, OF NEW YORK, N. Y., ASSIGNOR TO DICTAPHONE CORPORATION, OF BRIDGEPORT, CONNECTICUT, A CORPORATION OF NEW YORK.

SUPPORTING DEVICE.

Application filed May 20, 1924. Serial No. 714,536.

This invention relates to supporting devices, such as tablets or shelves, and, in a more specific aspect, to tablets or shelves adapted to be attached to a side of dictating machines and 5 the like for supporting writing pads and other articles.

It is an object of this invention to provide a shelf of the nature described.

Other objects and advantages of the invention will appear hereinafter.

In the accompanying drawing, which illustrates one embodiment of this invention,

Figure 1 is a perspective view of a shelf provided with means for attaching it to the 15 frame of a dictating machine without the use of tools, the shelf being shown attached to a dictating machine.

Fig. 2 is a detail sectional view of a clamping device for holding a writing pad or work- 20 sheets on the shelf.

Fig. 3 is a side elevation of the dictating machine and attached shelf shown in Fig. 1.

Fig. 4 is a sectional view showing the means for securing the shelf to the end of a machine 25 frame.

Fig. 5 is a side view of a portion of the dictating machine shown in Fig. 3, with the shelf removed.

As shown in the accompanying drawings, 30 the supporting device or shelf comprises a plate 10 which is held to the side 11 of the dictating machine frame 12 by means of a hook 13, which is preferably formed integral with the plate 10. The hook 13 has an upwardly extending portion 14, a horizontal portion 15, and a downwardly extending portion 16 to hook over and engage the top-flange 17 of the frame-end 11. In Fig. 1, the top- 35 plate 18 of the dictating machine is broken away to show how the hook 13 engages the top-flange 17.

In applying the plate 10 to the machine, the top-plate 18 is swung upwardly upon a hinge 18^a which connects it at its rear edge to 40 the frame 12; and to do so, it is merely necessary to remove the thumb-nuts 19, (only one of which is shown) which secure the front edge of the top-plate 18 to the frame 12.

At its front-end the plate 10 is held to the 45 side 11 of the dictating machine by an integral ear 20 which is first passed through one of the ventilating apertures 21 provided in the side 11 while in a vertical position. Then the plate 10 is swung rearwardly to a position 50 where the hook 13 engages the top flange 17

of the frame 12. The ear 20 is provided with a reduced portion 22 which is substantially as wide as the aperture 21, while beyond the reduced portion it has a greater width than the perforation 21, so that the ear 20 cannot be 60 withdrawn through the aperture when the plate 10 is substantially in horizontal position.

It will thus be seen that the shelf is connected to the frame and is supported along its 65 inner edge by the hook 13 at the rear, and the ear 20 at the front. The outside portion of the plate 10 is supported by a bracket 23 having at its inner end, an upwardly extending arm 24, and by directly below the latter a claw 70 25. The arm 24 is adapted to engage an aperture 21^a near the top of the side 11, and the claw 25 is adapted to engage an aperture 21^b in the row below. In applying the bracket to the machine, the arm 24 is first inserted into 75 the aperture 21^a while the bracket is held vertically. Then the bracket is swung downwardly until the claw 25 extends into the perforation 21^b directly beneath the perforation 21^a. This bracket is then allowed to drop 80 bodily until a notch 26 engages the bottom wall of the perforation 21^b, while the arm 24 engages the side 11 at the portion directly above the perforation 21^a.

At its outer end, the bracket is provided 85 with a lug 27 adapted to extend into an opening 28 provided in an ear 29 extending downwardly from the outer edge of the plate 16. This connection of the plate 10 and bracket 23 securely unites the two parts and holds the 90 plate 10 from being raised upwardly at its end, as well as supporting it in proper position.

To further support the plate 10, the bracket 23 is provided with an arm 30, riveted there- 95 to at 31 and extending forwardly and downwardly from the main body portion of the bracket. At its end, the arm 30 is provided with a lug 32 bent parallel with the main body portion of the bracket 23 and adapted to extend into an opening 33 provided in an ear 34, 100 extending downwardly from the outer edge of the plate 10. The lug 32 engages the ear 34 in the same manner that the lug 27 engages the ear 29.

The location of the ear 34 is substantially opposite that of the ear 20, which secures the plate 10 to the machine at its inside portion.

In applying the supporting device to the machine, the bracket 23 is first attached, and 110

then the plate 10 is mounted on the machine, all as above described. Then, the ears 29 and 33 are sprung outwardly by hand until the lug 27 and lug 32 respectively are engaged in the openings 28 and 33. It will thus be seen, that the device may be attached to the dictating machine without the use of tools and when it is so attached, it is securely held in place.

The plate 10, as illustrated in the accompanying drawing, is adapted to support a pad 35 in an inclined position, as shown in Fig. 3, so that it may receive pencil notations made by the dictator while using the machine. It is, of course, obvious that the supporting device may be used for other purposes, such as a shelf to hold material other than a writing pad.

The supporting device as shown in the accompanying drawing is provided with a pair of upwardly extending lugs 36, adapted to engage the top of the pad to locate the pad properly on the tablet, and a clamp 37 to hold the pad thereon against accidental displacement. As may be best seen in Fig. 2, the clamp comprises a plate 38 having downwardly extending ears 39 carried by a pin 40 mounted in ears 41 of a rearward extension 42 of the plate 10. The clamping plate 38 is provided with a finger-piece 43 opposite a similar finger-piece 44 on the rear extension 42, and is held in operative position against the pad by means of a spring 45. This spring is U-shaped and has one of its legs provided with an enlarged end 46 engaging the finger-piece 44, and is confined thereto by an upwardly extending flange 47 integral with the finger-piece 44. The other leg engages the finger-piece 43 of the clamping plate 38. The clamping plate 38 preferably has a depression 48 adapted to fit the thumb, and thus facilitate its operation.

At its forward end, the plate 10 is provided with a pair of curved arms 49 forming a well, for the reception of a pencil 50. The well has a cut-out at 51 to facilitate the removal of the pencil therefrom. The pencil is preferably carried by a holder 52 attached to a bead-chain 53, the other end of which has

its ring 54 secured to the ear 34 by passing through a perforation 55, provided in the ear 50 for the purpose.

The supporting device, as shown in the drawings, is mounted at the right end of the dictating machine directly in line with the sound recording and reproducing mechanism 55 56 and the record-supporting mandrel 57, so that notations relating to the matter dictated, such as corrections, ends-of-letters, etc., may be conveniently made. The supporting device may also be applied to the 60 transcribing machine in the same manner as that shown in connection with the dictating machine.

While the embodiment of the invention herein illustrated is shown as being applied to the side of a dictating machine and by utilizing the perforated end of the dictating machine to support it, it should be understood that for machines of other kinds the bracket 23 could be adapted to engage existing parts of the machines, and the plate 10 would also be provided with means for engaging existing parts of the machine to which it is applied. Consequently, it should be distinctly understood that this invention 75 is not limited to the form herein shown, and that variations and modifications may be made within the scope of the invention and portions of the improvements may be used without others.

Having now described the invention, what is claimed as new, and for which it is desired to obtain Letters Patent, is:

In combination, a frame having a portion provided with perforations; a plate; means on the plate for engaging over said portion, and perforation-engaging means on the plate for mounting the plate on said frame; a bracket for the plate; perforation-engaging means on the bracket adapted to engage said portion; and means on the plate adapted to engage the bracket.

Signed at Bridgeport, in the county of Fairfield, and State of Connecticut, this 19th day of May, 1924.

CHARLES K. WOODBRIDGE.
